BALL MARKER

Jack Holiday Hochman, Dayton, Ohio

Application April 15, 1947, Serial No. 741,641

1 Claim. (Cl. 101—333)

1

This invention relates to a ball marker and more particularly to a device for manually printing names on golf balls.

It is an object of this invention to provide a golf ball marking apparatus which is inexpensive, compact, and easy to operate.

A further object of this invention is to provide a simplified means for firmly holding a golf ball while printing a name on the outer surface of the golf ball cover.

More particularly, it is an object of this invention to provide a ball holding device which grips the ball at spaced points.

Another object of this invention is to provide a golf ball holding device having a first recess for holding either the golf ball or the golf ball marking device and having a second recess for holding an ink pad.

Further objects and advantages of the present invention will be apparent from the following description, reference being had to the accompanying drawings wherein a preferred form of the present invention is clearly shown.

In the drawings:

Figure 1 is a pictorial view showing a golf ball marker in use;

Figure 2 is a plan view of the golf ball holding device;

Figure 3 is a sectional view taken on line 3—3 of Figure 2;

Figure 4 is a fragmentary sectional view showing the arrangement of the inking pad;

Figure 5 is a view showing the construction of the ink pad holder; and

Figure 6 is an elevational view of the device.

Referring now to the drawing wherein I have shown a preferred embodiment of my invention, reference numeral 10 designates a base which is preferably made in the form of a molded plastic element having a substantially centrally disposed cylindrical recess 12. The diameter of the recess 12 is slightly less than the diameter of a golf ball whereby the exposed edges 14 of the recess serve to firmly grip the golf ball. An intersecting oblong recess 16 is provided which serves a multiple purpose to be explained more fully hereinafter.

It will be noted that by virtue of the above described recess formation the ball engaging edges 14 are not continuous whereby there is less tendency of the ball shifting in the recess when pressure is applied to the ball during the marking operation.

The name to be applied to the ball is impressed into the ball by means of steel type 18 carried by a holder generally designated by the reference

2

numeral 20. The holder 20 has a handle portion 24 and a type holding portion 22. The type holding portion 22 is oblong in shape and is slightly smaller than the oblong recess 16 formed in the upper face of the block 10 whereby the portion 22 may be inserted into the recess 16 when not in use. The handle portion 24 is considerably larger in cross sectional area than the portion 22 and serves to limit movement of the type holder into the recess 16 and also serves to substantially close the central opening in the base 10. In order to align the printing with the original markings on the ball the original markings or pattern on the golf ball may be lined up with the straight edges 17 of the oblong recess 16 and these same edges may be used for lining up the type holder during the marking operation.

By virtue of the above described arrangement, it is apparent that the oblong recess 16 not only serves as a holder for the element 20 but also facilitates the aligning of the type holder with the original markings on the ball. Furthermore, the removal of material on opposite sides of the circular recess 12 improves the grip on the ball due to the fact that the ball is gripped at spaced points rather than along one continuous line.

It will be noted that the type 18 is arranged in a straight line whereby only a few letters of the name contact the ball at any one time during the ball marking operation. In view of this arrangement the pressure applied to each letter impressed on the ball is much greater than if all of the letters were to contact the ball at one time.

A circular recess 26 is provided in the one corner of the base 10 as indicated for the reception of the ink pad holder 28. The holder 28 is recessed at 30 for the reception of the inked pad 32 which is used for dabbing ink on to the steel type 18 prior to marking of the ball. The holder 28 is provided with a handle portion 34 which serves to limit the inward movement of the element 28 within the recess 26.

While the form of embodiment of the invention as herein disclosed, constitutes a preferred form, it is to be understood that other forms might be adopted, all coming within the scope of the claim which follows.

What is claimed is as follows:

An article of manufacture comprising a base having a recess formed in one face thereof adapted to hold a golf ball while a name is impressed on the ball, said recess comprising a circular portion having a diameter slightly less than the diameter of a golf ball and having an inter-

secting oblong portion having a length greater than the diameter of said circular portion but having a width less than the diameter of said circular portion whereby opposed arcuate ball engaging edges are formed for engaging a ball, and 5 a type holder having a type supporting portion adapted to project into said oblong portion of said recess when not in use and having a handle portion larger in cross section than said oblong portion for substantially closing said first named recess, said handle portion having a straight edge portion which is adapted to be lined up with one edge of said oblong portion of said recess during the process of printing a name on a ball.
